UNITED STATES PATENT OFFICE

2,340,270

DIESEL ENGINE CONTROL

Chester P. Leliter, La Porte, Ind., assignor to
 Allis-Chalmers Manufacturing Company, Milwaukee, Wis., a corporation of Delaware

Application May 2, 1941, Serial No. 391,442

14 Claims. (Cl. 123—140)

This invention relates generally to the control of internal combustion engines and more particularly to mechanism for controlling the fuel and air supply of internal combustion engines employing an oil bath type of air cleaner.

Most of the types of engines, in which there is an internal vaporizing of the fuel, for example, Diesel engines, employ an oil bath type of air cleaner and the speed and the power output of the engine are generally controlled by a speed responsive governor operatively associated with the usual fuel injection equipment so as to vary the quantity of fuel delivered to the combustion chamber in accordance with changes in load sufficient to effect a variation in engine speed. The control mechanism usually employed includes a means for varying the speed setting of the governor and a means for completely terminating fuel feed when it is desired to stop the engine. However, in Diesel engines it is impractical to vary the air flow since the air flow is a function of engine speed and a material reduction in the weight or the density of the air drawn into the engine cylinder, materially reduces the compression pressure and temperature, thereby rendering ignition extremely difficult if not impossible without the aid of some positive ignition means, such as a glow or spark plug. In fact, the air flow is throttled in only a few types of semi-Diesel engines equipped with a positive ignition means and then only to a relatively slight extent in comparison with the degree of throttling usually employed in the external mixing type of engine; i. e., the ordinary gasoline engine.

Consequently, when an internal mixing type of engine employing an oil bath type of air cleaner is drivingly connected with a load which is capable of being accelerated by some means other than the driving engine, such, for example, as a vehicle on a steep down grade, the fuel feed will be reduced to a minimum commensurate with idling operation, but the air flow will increase as a function of engine speed, and if the load accelerates the engine, the increased air flow may carry a sufficient quantity of oil from the air cleaner over into the engine to cause the engine to run away. Complete termination of fuel feed will not prevent the engine from running away and the engine and the vehicle invariably suffer serious damage before the usual brakes can be applied and the speed decreased to a safe limit. This condition has actually occurred in connection with Diesel engine driven tractors and motor graders, and although attempts have been made to remedy this defect by redesigning the air clean-

er to prevent oil carry-over into the engine, these attempts have not been successful.

It is therefore an object of this invention to provide an improved engine control operative to prevent the engine from running away.

Another object of this invention is to provide an improved and simplified engine control which can be manipulated by the movements of a single element or lever to vary the speed setting of the governor and to completely terminate the flow of fuel and air when it is desired to stop the operation of the engine.

Still another object of this invention is to provide an improved and simplified engine control which can be manipulated by the movements of a single element or lever to effect the desired regulation and which will remain in any selected position without the aid of latching or locking means.

20 A further object of this invention is to provide an improved and simplified engine control mechanism which will remain in any selected position without the aid of latching or locking means and which can be readily moved to a different desired position with a minimum of effort.

The invention accordingly consists of the various features of construction, combinations of elements, and arrangements of parts as more particularly pointed out in the appended claims and in the detailed description, in which:

Fig. 1 schematically illustrates a Diesel engine embodying the invention;

Fig. 2 is an enlarged sectional view of the form of friction disk holding mechanism employed in the control arrangement shown in Fig. 1; and

Fig. 3 is an enlarged sectional view of the air valve and fuel shutoff lever shown in Fig. 1.

Referring to the drawing and particularly Fig. 1, it is seen that the control is shown as applied to a multicylinder Diesel engine 1 having a known form of fuel injection pump 2 and an oil bath type of air cleaner 3 which is operatively connected with the usual riser portion 4 of the intake manifold 5. Fuel under suitable pressure is conducted from the injection pump 2 into the usual engine cylinders or combustion chambers through conduits 6 and the quantity of fuel injected is controlled in a well known manner by means of 45 a slidably mounted pump control rod 7. Fuel from a suitable source (not shown) is conducted into the fuel injection pump 2 through a pipe 8 which is provided with a control valve 9. Details of the air cleaner and fuel pump are not essential 50 for a complete understanding of this inven-

tion and such features have been omitted in the interest of simplicity.

The riser portion 4 of the intake manifold 5 is provided with an air valve 10 to which is secured an actuating arm 11 which has an intermediate portion operatively connected with one end of a link 12 by means of a lost motion connection 13. The other end of link 12 is operatively connected with the stem portion of the fuel valve 9. A biasing spring 14, which has one end fixedly connected to the intake manifold 5 and its other end connected with an intermediate portion of the arm 11, acts to maintain the throttle valve 10 and the fuel valve 9 in their fully open positions shown. Further movement of the arm 11 in a counterclockwise direction is prevented by the fuel valve engaging the inner surface of the valve casing. However, the same result can be accomplished, if desired, by the use of suitable stops (not shown) positioned to engage the arm 11 or any other part operatively connected thereto.

The shown position of the injection pump control rod 7 permits the injection of just sufficient fuel to maintain the engine operating under no load or idling conditions. The rod 7 is operatively connected with a slidable sleeve member 15 which in turn is operatively connected with the flyball mechanism 16 of a known form of centrifugal speed governor 17. The governor 17 is operatively associated with the engine driven shaft 18 employed for actuating the fuel injection pump 2. A lever 19 which is fulcrumed intermediate its ends has one end operatively connected with flyball mechanism 16 of governor 17 and its other end operatively connected with one end of a yoke member 21 which has its other end slidably mounted on a reciprocable rod member (hereinafter termed a rod) 22. The end of the rod 22 which extends within the yoke 21 is provided with a transversely extending pin 23 adapted to engage the opposite inner end portions of the yoke 21. This arrangement provides a lost motion connection between the rod 22 and the lever 19. The rod 22 is provided with a lateral projection 24 arranged to extend in close proximity with respect to the end of the arm 11 when the rod 22 is in the low idle position shown.

This construction permits the rod 22 to be moved a sufficient distance to the left from the position shown in Fig. 1 to effect a closure of the air valve 10 and the fuel valve 9 thereby completely terminating the air and fuel supply without effecting a movement of the lever 19. This operation completely terminates engine operation irrespective of the prevailing conditions of speed and in this connection it is preferable to provide means such as the lost motion connection 13 between the air valve arm 11 and the link 12 for effecting complete closure of the fuel valve 9 before the air valve 10 reaches its fully closed position as this sequential operation of the fuel and air valves continues the flow of air for a short period of time sufficient to consume the fuel which may continue to enter the combustion chamber for a short time after the fuel valve 9 is fully closed. A movement of the rod 22 toward the right from the position shown in Fig. 1 moves the lever 19 in a clockwise direction which through the medium of the governor flyball mechanism 16 moves the pump control rod 7 to increase fuel injection and conditions the governor 17 to maintain a higher speed dependent upon the extent the rod 22 is moved in this direction. During movements of the rod 22 toward the right from

the position shown, the spring 14 acts to maintain the fuel valve 9 and the air valve 10 in their fully open positions.

Movement of the rod 22 in either direction from the position shown is effected by means of a rod 26 which in turn is adapted to be actuated from a remote point by a single hand lever or the like (not shown). Rod 26 is operatively connected with rod 22 by means of a holding mechanism 27 (the rod 26 and the mechanism 27 constituting actuating means for the rod member 22), which as best seen in Fig. 2 is in the nature of a friction brake comprising a symmetrical hollow casing 28 presenting opposed inner annular surfaces 29 and 31 arranged in coaxial spaced relation, a shaft member 32 extending through and rotatably supported in said casing in coaxial relation with respect to said annular surfaces, a pair of annular resilient disks 33 and 34 mounted in spaced sliding non-rotative relation on a sleeve member 35 which is secured on the portion of the shaft member 32 confined within the casing 28 said disks being provided on their outwardly facing surfaces with annular lining elements 36 and 37 arranged for frictional engagement with the surfaces 29 and 31, respectively, and a spring 38 interposed between said disks effective to at all times maintain firm frictional engagement between the elements 36 and 37 and the surfaces 29 and 31. The casing 28 is fixedly secured to a stationary structure by any suitable means such as the bolts 39.

One end of the shaft member 32 is provided with a transversely extending arm 41 to the outer end portion of which is secured the rod 22 and the rod 26 and the other end of said shaft member is also provided with a transversely extending arm 42 to the outer end of which is secured one end of a spring 43 which has its other end secured to a suitable stationary structure. The arms 41 and 42, which move with shaft member 32, and the spring 43 are so arranged that when the arm 41 and rod 22 are in the low idle position shown, the longitudinal axis of the shaft member 32, arm 42 and spring 43 lie in a plane, i. e., the spring 43 does not act to produce a moment tending to turn the shaft member 32, and that when the arm 41 is moved in either a clockwise or a counterclockwise direction from the position shown, the spring produces a moment acting to urge the arm 41 in the direction in which it has been moved. In other words, the spring 43 acts to prevent vibration and the action of the biasing spring 14, the spring biased governor flyball mechanism 16, and other biasing means which may be employed for effecting a return of the arm 41 to its low idle position shown without the aid of a positive latching device such as is generally provided on the usual actuating handle or lever (not shown) and with the aid of only a minimum degree of pressure between the friction disks 33 and 34 and the stationary casing 28. Consequently, the actuating rod 26 can be readily and quickly moved with minimum effort to effect a desired change in the setting of the control devices, i. e., the governor 17 and the fuel and air control valves 9 and 10, respectively.

The operation of the illustrated control arrangement should be obvious in view of the foregoing and a further description in this connection is deemed unnecessary for a complete understanding of the invention. The invention is of general application and it should therefore be understood that it is not desired to limit the invention to the exact mode of operation and to the exact details of construction herein shown.

and described as various modifications within the scope of the appended claims may occur to persons skilled in the art.

It is claimed and desired to secure by Letters Patent:

1. In combination, an internal combustion engine, means for separately conducting fuel and air into a combustion chamber of said engine, means controlling fuel feed and including a movable member positionable to effect variations in fuel feed between predetermined high and low operating limits and positionable to effect a substantially complete termination of fuel feed, actuating means for selectively positioning said member to effect desired variations in the fuel feed between said predetermined limits and to effect a substantially complete termination of fuel feed, means controlling air flow and including a movable element operable when in one position to effect a substantially complete termination of air flow and operable when in another position to effect an air flow sufficient for engine operation, and connections rendering said member operative to control the position of said element and rendering the movement of said member to its said fuel feed terminating position effective to move said element to its said one position.

2. In combination, an internal combustion engine, means for separately conducting fuel and air into a combustion chamber of said engine, means controlling fuel feed and including a movable member positionable to effect variations in fuel feed between predetermined high and low operating limits and positionable to effect a substantially complete termination of fuel feed, actuating means for selectively positioning said member to effect desired variations in the fuel feed between said predetermined limits and to effect a substantially complete termination of fuel feed, means controlling air flow and including a movable element operable when in one position to effect a substantially complete termination of air flow, and operable when in another position to effect an air flow sufficient for engine operation, and connections rendering said element responsive to predetermined movements of said member and the movement of said member to its said fuel feed terminating position effective to move said element to its said one position, said connections also rendering the movement of said member from its said fuel feed terminating position to its said low operating limit position effective to move said element from its said one position to its said other position.

3. In combination, an internal combustion engine, means for separately conducting fuel and air into a combustion chamber of said engine, means controlling fuel feed and including a movable member positionable to effect variations in fuel feed between predetermined high and low operating limits and positionable to effect a substantially complete termination of fuel feed, actuating means for selectively positioning said member to effect desired variations in the fuel feed between said predetermined limits and to effect a substantially complete termination of fuel feed, means controlling air flow and including a movable element operable when in one position to effect a substantially complete termination of air flow, and operable when in another position to effect maximum air flow, and connections rendering said element responsive to predetermined movements of said member and the movement of said member to its said fuel feed terminating position effective to move said ele-

ment to its said one position, said connections also rendering a movement of said member from its said fuel feed terminating position to its said low operating limit position effective to move said element from its said one position to its said other position, and means acting to maintain said element in its said other position while said member is moved to vary the fuel feed between said predetermined limits.

10 4. In combination, an internal combustion engine, means for separately conducting fuel and air into a combustion chamber of said engine, means controlling fuel feed and including a movable member positionable to effect variations in fuel feed between predetermined high and low operating limits, and positionable to effect a substantially complete termination of fuel feed, means controlling air flow and including a movable element operable when in one position to effect a substantially complete termination of air flow, and operable when in another position to effect an air flow sufficient for engine operation, and connections rendering said member operative to control the position of said element, and rendering the movement of said member to its said fuel feed terminating position effective to move said element to its said one position.

15 5. In combination, an internal combustion engine, means for separately conducting fuel and air into a combustion chamber of said engine, means controlling fuel feed and including a movable member positionable to effect variations in fuel feed between predetermined high and low operating limits, and positionable to effect a substantially complete termination of fuel feed, means controlling air flow and including a movable element operable when in one position to effect a substantially complete termination of air flow, and operable when in another position to effect an air flow sufficient for engine operation, connections rendering said member operative to control the position of said element, and rendering the movement of said member to its said fuel feed terminating position effective to move said element, to its said one position, and actuating means operable to selectively position said member, said actuating means embodying a holding device comprising a friction brake having a movable part, and mechanism operatively connecting said part with said member for selectively moving said member away from a predetermined position in two different directions.

20 6. In combination, an internal combustion engine, means for separately conducting fuel and air into a combustion chamber of said engine, means controlling fuel feed and including a movable member positionable to effect variations in fuel feed between predetermined high and low operating limits, and positionable to effect a substantially complete termination of fuel feed, means controlling air flow and including a movable element operable when in one position to effect a substantially complete termination of air flow and operable when in another position to effect an air flow sufficient for engine operation, connections rendering said member operative to control the position of said element and rendering the movement of said member to its said fuel feed terminating position effective to move said element to its said one position, and actuating means operable to selectively position said member, said actuating means embodying a holding device comprising a friction brake having an angularly movable part, and mechanism operatively connecting said part with said member for se-

lectively moving said member away from a predetermined position in two different directions, said mechanism including a force producing means connected with said part and being operative, when said member is in said predetermined position to act on said part in a non-moment producing manner, and being also operative as said part is being moved to displace said member from said predetermined position in either one of said two different directions, to produce an increasing moment acting to urge said part in the direction of its movement.

7. In combination, an internal combustion engine, means for separately conducting fuel and air into a combustion chamber of said engine, means controlling fuel feed and including a member movable relative to a predetermined position in two different directions, one of which effects an increase in fuel feed and the other of which effects a decrease in fuel feed, actuating means rendering said member selectively movable in said two different directions to effect the variations in fuel feed necessary for normal operation and movable an additional distance in said other direction to effect a substantially complete termination of fuel feed, means controlling air flow and including a movable element operable when in one position to effect a substantially complete termination of air flow and operable when in another position to effect an air flow sufficient for engine operation, and connections rendering said member operative to control the position of said element and rendering the movement of said member through said additional distance effective to move said element to its said one position.

8. In combination, an internal combustion engine, means for separately conducting fuel and air into a combustion chamber of said engine, means controlling fuel feed and including a member movable relative to a predetermined position in two different directions, one of which effects an increase in fuel feed and the other of which effects a decrease in fuel feed, biasing means acting to retain said member in said predetermined position, actuating means rendering said member selectively movable in said two different directions to effect the variations in fuel feed necessary for normal operation, and movable an additional distance in said other direction to effect a substantially complete termination of fuel feed, means controlling air flow and including a movable element operable when in one position to effect a substantially complete termination of air flow, and operable when in another position to effect an air flow sufficient for engine operation, and connections rendering said member operative to control the position of said element and rendering the movement of said member through said additional distance effective to move said elements to its said one position, said actuating means embodying a holding device comprising a friction brake having a movable part, and mechanism interconnecting said part and member for simultaneous movement, said mechanism including a force producing portion effective to act in opposition to said biasing means with increasing effectiveness as said member is moved away from its said predetermined position in either one of said two different directions.

9. In combination, an internal combustion engine, means for separately conducting fuel and air into a combustion chamber of said engine, means controlling fuel feed and including a member movable relative to a predetermined position in two different directions, one of which effects an

increase in fuel feed and the other of which effects a decrease in fuel feed, actuating means rendering said member selectively movable in said two different directions to effect the variations in fuel feed necessary for normal operation, and movable an additional distance in said other direction to effect a substantially complete termination of fuel feed, means controlling air flow and including a movable element operable when in one position to effect a substantially complete termination of air flow and operable when in another position to effect an air flow sufficient for engine operation, and connections rendering said member operative to control the position of said element and rendering the movement of said member through said additional distance effective to move said element to its said one position, said actuating means embodying a holding device comprising a friction brake having an angularly movable part, and mechanism interconnecting said part and member for simultaneous movement, said mechanism including a force producing portion which is ineffective when said member is in its said predetermined position, to act on said part in a moment producing manner, and which is effective as said part is being moved to displace said member from its said predetermined position in either one of said two different directions, to produce an increasing moment acting to urge said part in the direction of its movement.

10. An internal combustion engine control system comprising means controlling fuel feed and including a member movable relative to a predetermined position in two different directions, biasing means acting to retain said member in said predetermined position, and actuating means rendering said member selectively movable in said two different directions to effect desired variations in fuel feed, said actuating means embodying a holding device operative to prevent said biasing means from effecting a return of said member to its said predetermined position, said holding device comprising a continuously acting friction brake having a movable part operatively connected to and movable with said member, and a force producing means operatively connected with said part, so as to act in opposition to said biasing means with increasing effectiveness as said member is moved away from its said predetermined position in either one of said two different directions.

11. An internal combustion engine control system comprising means controlling fuel feed and including a member movable relative to a predetermined position in two different directions, and actuating means rendering said member selectively movable in said two different directions to effect desired variations in fuel feed, said actuating means embodying a holding device comprising a friction brake having an angularly movable part operatively connected to and movable with said member, and a force producing means connected with said part, and being operative when said member is in its said predetermined position to act on said part in a non-moment producing manner, said force producing means being also operative as said part is being moved to displace said member from its said predetermined position in either one of said two different directions, to produce an increasing moment acting to urge said part in the direction of its movement.

12. An internal combustion engine control system comprising means controlling fuel feed and

including a member movable relative to a predetermined position in two different directions, and actuating means rendering said member selectively movable in said two different directions to effect desired variations in fuel feed, said actuating means embodying a holding device comprising a friction brake having a movable part operatively connected to and movable with said member, and a force producing means connected with said part and being operative as said part is being moved to displace said member from its said predetermined position in either one of said two different directions, to produce an increasing force acting to urge said part in the direction of its movement.

13. An internal combustion engine control system comprising means controlling fuel feed and including movable fuel feed regulating and cut-off apparatus, means biasing said control means to a selected fuel feeding position, a member movable in two different directions relative to a predetermined position, and actuating means operable to selectively move said member relative to said predetermined position in either one of said two different directions, and including connections rendering selected movements of said member effective to move said apparatus away from said selected position to fuel feed regulating positions and to a fuel feed terminating position, said actuating means also including a friction brake holding device and parts acting to progressively decrease the effectiveness of the means biasing said apparatus to said selected position as said member is moved away from said

predetermined position in either one of said two different directions.

14. In combination, an internal combustion engine, means for separately conducting fuel and air into a combustion chamber of said engine, means controlling fuel feed and including movable fuel feed regulating and cut-off apparatus, means biasing said control means to a selected fuel feeding position, means controlling air flow and including a movable element operable when in one position to effect a substantially complete termination of air flow, and operable when in another position to effect an air flow sufficient for engine operation, a member movable in two different directions relative to a predetermined position, and actuating means operable to selectively move said member relative to said predetermined position in either one of said two different directions, and including connections rendering said member operative to control the position of said apparatus and the position of said element, and rendering a predetermined movement of said member operative to effect a movement of said apparatus to its fuel feed terminating position, and to effect a movement of said element to its said one position, said actuating means also including a friction brake holding device and parts acting to progressively decrease the effectiveness of the means biasing said apparatus to said selected position as said member is moved away from said predetermined position in either one of said two different directions.

CHESTER P. LELITER.

CERTIFICATE OF CORRECTION.

Patent No. 2,340,270.

January 25, 1944.

CHESTER P. LELITER.

It is hereby certified that error appears in the printed specification of the above numbered patent requiring correction as follows: Page 3, first column, line 43, claim 2, line 70, claim 3, same page, second column, line 21, claim 4, line 39, claim 5, page 4, first column, line 54, claim 8, and page 5, second column, line 12, claim 14, after "flow" strike out the comma; page 3, second column, line 16, claim 4, and line 34, claim 5, after "limits" strike out the comma; page 3, second column, line 24, claim 4, lines 42 and 45, claim 5, and page 5, second column, line 22, claim 14, after "element" strike out the comma; page 4, first column, line 48, claim 8, and second column, line 5, claim 9, after "operation" strike out the comma; line 25, claim 9, after "manner" strike out the comma; line 48, claim 10, after "part" strike out the comma; page 5, first column, line 25, claim 13, for "directions," read --directions--; and second column, line 19, claim 14, after "directions" strike out the comma, line 25, claim 14, after "position" strike out the comma; and that the said Letters Patent should be read with this correction therein that the same may conform to the record of the case in the Patent Office.

Signed and sealed this 11th day of April, A. D. 1944.

Leslie Frazer
